GRINDING WHEEL TRUING APPARATUS

Charles C. Alvord, Worcester, Mass., assignor to
Norton Company, Worcester, Mass., a corpora-
tion of Massachusetts

Application December 10, 1938, Serial No. 244,883

10 Claims. (Cl. 125—11)

This invention relates to grinding machines, and more particularly to a truing apparatus for truing a plurality of spaced, different diameter grinding wheels.

5 One object of the invention is to provide a simple and thoroughly practical truing apparatus for truing a predetermined form on a grinding element. Another object of the invention is to true a plurality of closely spaced cylindrical portions of different diameters on one or more grinding elements. Another object of the invention is to provide an improved truing apparatus whereby a single truing tool is arranged to true a plurality of spaced grinding wheels in a multi-wheel grinding machine. Another object of the invention is to provide a truing apparatus for a multiple wheel grinding machine, in which a single truing tool is traversed across the faces of a plurality of grinding wheels to true the same to predetermined relative diameters. A further object of the invention is to provide an improved hydraulically operated multiple wheel truing apparatus. A further object of the invention is to provide a power reciprocated, hydraulically actuated, cam controlled truing tool which is arranged for movement in a path successively to true either a form on the periphery of a single grinding wheel or to true a plurality of grinding wheels of different diameters. Other objects will be in part obvious 30 or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

40 Fig. 1 is a front elevation of the improved truing apparatus mounted on a wheel slide, having the wheel guard removed;

Fig. 2 is a fragmentary diagrammatic view of the hydraulic control and operating system, showing the cam and follower for controlling the lift of the grinding wheel;

Fig. 3 is a rear elevation, on a reduced scale, of the truing apparatus;

50 Fig. 4 is a fragmentary sectional view, on an enlarged scale, taken approximately on the line 4—4 of Fig. 3;

Fig. 5 is a plan view of the improved truing apparatus; and

55 Fig. 6 is a fragmentary diagrammatic view,

showing the path of movement of the truing tool during a truing operation.

The improved truing apparatus has been illustrated in the drawings as mounted fixedly on top of a wheel slide 10 which rotatably supports a 5 wheel spindle carrying a plurality of spaced grinding wheels 12 and 13 of different sizes and diameters.

The wheel slide 10 supports a truing apparatus frame or base 14. An adjustable horizontally 10 arranged member 15 is pivotally connected by means of a stud 16 with the frame 14. An adjusting screw 17 threaded into a lug 18 projecting from the base 14 serves to adjust the member 15 about its stud or pivot 16 to facilitate adjusting 15 the position of the member 15 relative to the base. A lock nut 19 serves to lock the screw 17 in an adjusted position. The member 15 may be clamped in adjusted position on the frame 14 by means of clamping screws 25 which pass through elongated 20 slots 26 in the lugs 27 on the frame 14 and are screw threaded into the member 15. A dovetailed slideway 20 is formed integral with the member 15 and is arranged to support a horizontally movable slide 21 having a dovetailed slideway 22 25 which mates with the dovetailed slideway 20. An adjustable tapered gib 23, interposed between the dovetailed ways 20 and 22, serves to take up lost motion between the fixed and movable parts of the slide. A screw 24 is provided to facilitate end- 30 wise adjustment of the gib 23.

The horizontal slide 21 is provided with a vertically extending member 28 which is formed either integral therewith or fixedly mounted thereto. The vertically extending portion 28 of 35 the horizontal slide 21 is provided with a dovetailed slideway 29 which supports a vertically movable slide 30 having a mating dovetailed slideway 31. An adjustable tapered gib 32 serves to take up lost motion between the dovetailed slideways 29 and 31, and a screw 33 serves to facilitate 40 adjustment of the gib 32.

A second vertically arranged slide 35 is supported by a dovetailed slideway 36 formed in the member 28. The dovetailed slideway 36 is provided with a tapered gib 37 having an adjusting screw 38. The slide 35 is preferably arranged so that it may be moved vertically during the horizontal movement of the slide 21.

The vertical slide 30 adjustably supports a 50 truing tool holder which in the present case is formed as a cylindrical bar 40 which is slidably keyed in an aperture 41 formed in a projection 42 of the slide 30 by means of binding screws 43 and 44. The truing tool support 40 carries 55

at its outer end a truing tool 45 having a diamond point 46 arranged for successively truing the peripheral surfaces of the grinding wheels 12 and 13.

5 The slide 35 is preferably adjustably connected to the slide 30 so that during the traversing movement of the horizontal slide 21, the vertical slides 30 and 35 are moved together in a vertical direction to control the path of movement of the diamond or truing tool 46. The slide 35 is provided with a forwardly extending boss or lug 50. A vertically extending feed screw 51 is rotatably connected to the lug 50 and extends downwardly through a nut 52 carried by or formed integral 10 with the vertically arranged slide 30. The lower end of the feed screw 51 is journaled in a suitable bearing (not shown) formed within a casing 54 which is fixedly mounted to the vertical slide 28. A worm gear 55 meshes with a worm gear 56 supported on the inner end of a rotatable shaft 57. The shaft 57 is journaled in bearings (not shown) within the casing 54 and is provided at its outer end with a manually operable hand wheel 58. By adjustment of the manually operable wheel 58, the feed screw 51 may be rotated 15 to adjust the position of the slide 30 relative to the vertically movable slide 35.

A power operated traversing mechanism is provided for producing a longitudinal traversing or 20 reciprocating movement of the horizontally movable slide 21 to traverse the truing tool 46 relative to the periphery of the grinding wheels 12 and 13. In the preferred form, a fluid pressure traversing or reciprocating mechanism is provided comprising a cylinder 60 which is formed within the member 15. A slidably mounted piston 61 is mounted within the cylinder 60 and is connected to one end of a piston rod 62, the other end of which is fastened by nuts 63 to an end cap 64 25 formed integral with or fixedly mounted on the end of the horizontal slide 21. As fluid under pressure is admitted either through a pipe or passage 65 into a cylinder chamber 66 within the cylinder 60, or through a pipe or passage 67 into a cylinder chamber 68 within the cylinder 60, the piston 61 is moved longitudinally to traverse or reciprocate the horizontally arranged slide 21 to traverse the truing tool 46 across the face of the grinding wheels 12 and 13.

30 The admission of fluid under pressure to the cylinder chambers 66 and 68 is preferably controlled by a control valve 69 which in the present case is a rotary type valve. Fluid under pressure from a reservoir 70, preferably located within the base (not shown) of the machine, is pumped through a pipe 71 by means of a motor driven pump 12 which forces fluid under pressure through a pipe 73 to the control valve 69. An adjustable relief valve 74 is connected with the pipe line 73 so that if the pressure within the hydraulic system increases over the desired and set pressure, the valve 74 will exhaust excess fluid under pressure through a pipe 75 to the reservoir 70.

35 In the position of the valve 69 (Fig. 5), fluid under pressure passing through the pipe 73 enters a valve chamber 76 and passes out through a pipe or passage 65 which admits fluid under pressure to the cylinder chamber 66 to cause the piston 61 and the longitudinally movable slide 21 carrying the truing apparatus 46 to move toward the right into the full line position as indicated in Fig. 1. During this movement, fluid is exhausted from 40 the cylinder chamber 68, through the pipe 67,

through a valve chamber 78, and out through a pipe 79 and pipe 80.

A speed regulating valve or variable speed throttle valve 81 is provided in the pipe 80 and serves to regulate the exhaust of fluid through 5 the pipe 82 and thereby to regulate the traversing speed of the truing tool 46 across the operative face of the grinding wheels 12 and 13.

During the traverse of the truing tool, when it is not in operative engagement with the grinding wheel, it is desirable to traverse the diamond and its supporting slides at a fast rate to facilitate a rapid dressing operation. A by-pass valve 83 is provided. This valve is preferably a piston type valve having valve pistons 84 and 85 formed integral with a valve stem 86. The outer end of the valve piston 84 is provided with a conically shaped surface 87 which is arranged to serve as a follower in operative engagement with a cam plate 88 which is adjustably fastened to the slide 21 by 10 screws 89 and 90. A spring 91 within the valve 83 which is located between the valve piston 85 and the end cover of the valve casing 83 (Fig. 2) serves normally to hold the valve with the follower 87 in engagement with the cam 88. In the 15 position of the valve 83 as shown in Fig. 2, fluid from the pipe 80 enters the valve chamber located between the valve pistons 84 and 85 and passes out through a passage 92 and a pipe 93 into the pipe 82, thus by-passing the fluid around the 20 throttle valve 81 so as to traverse the truing tool 46 and its supporting slides at a rapid rate. When the slide 21 traverses longitudinally relative to the arrow point 87, the follower rides down onto a low portion 94 on the cam plate 88 which 25 serves to cut off the passage of fluid through the valve 83 by closing the port entering the passage 92, thus necessitating the exhaust of fluid through the needle valve 81 which is set to obtain the desired slow truing speed of the tool 46. The speed 30 of movement of the truing tool 46 is again changed to a faster traversing speed at the other end of the stroke after the diamond or truing tool 46 traverses out of contact with the grinding 35 wheels 12 and 13 being trued.

In truing a grinding wheel, it is desirable to reciprocate the truing tool across the surface of the wheel either one or more reciprocations for each truing operation. For many truing operations, a single complete reciprocation is sufficient to produce the desired results. In the disclosure in the drawings, a mechanism has been illustrated for controlling the valve 69 so that the truing tool 46 makes one complete reciprocatory stroke and then stops. A manually operable handle or knob 95 is fixed to the rotary part of the valve and may be rotated in a counterclockwise direction (Figs. 1 and 2) until a spring-actuated pawl 96 drops into engagement with a notch 97 in a plate 98 supported by the rotary part of the valve 69. This movement of the valve starts the traversing movement of the slide 21 and the truing tool 46 toward the left (Figs. 1 and 5) to traverse the truing tool 46 across the faces of the grinding wheels 12 and 13. The traversing movement of the truing tool 46 and slide 21 toward the left continues until an adjustably positioned collar or dog 99 carried by the slide 21 engages a cam surface 100 on the spring-pressed pawl 96, thereby withdrawing the pawl 96 from engagement with the notch 97. A weight 101 carried at the end of a lever 102 operating under the influence of gravity rocks the rotor of the valve 69 in a clockwise direction (Figs. 1 and 2) to reverse the position of the valve 69 and thereby 45

reverse the movement of the truing tool 46 and the slide 21 to traverse the same in the reverse direction across the peripheral faces of the grinding wheels 12 and 13, respectively. When the piston 61 engages the end of the cylinder 60 in its movement toward the right (Fig. 2), the truing tool 46 stops and remains in this position when the grinding operation is resumed.

In order that the truing tool 46 may true a plurality of spaced grinding wheels of different diameters, such as a pair of spaced wheels 12 and 13, respectively, it is desirable to provide an actuating mechanism to move the slides 30 and 35 vertically. In truing a plurality of wheels which are closely spaced relative to each other and whose diameters are different from each other, it is desirable to provide an actuating mechanism for the truing tool 46 to rapidly raise or lower the tool in a vertical direction when the truing tool 46 reaches a predetermined position in its traversing movement. A rotatable cam 110 is utilized to transmit a vertical movement to the slides 30 and 35. The rotatable cam 110 is supported on a shaft 111 which is supported on the vertical member 28 which is formed integral with the horizontal slide 21. The outer end of the shaft 111 is supported in a bearing 112 formed integral with a bracket 113 which straddles the slide 35 and is fixedly mounted to the vertical member 28. A follower 114 is fixedly mounted on the vertically movable slide 35 and is arranged to engage the periphery of the rotatable cam 110. The rotatable cam 110 is provided with a concentric portion 115 which, as illustrated in Fig. 2, is in engagement with the follower 114. The cam does not rotate during the passage of the truing tool 46 across the face of the grinding wheels. Consequently, with the concentric portion 115 it is not necessary to index the cam 110 to within very precise limits. As long as the follower 114 engages the concentric portion 115, the diamond or truing tool 46 will be accurately positioned for truing the periphery of the grinding wheel 12. A similar concentric portion 116 is provided which is of a shorter radius to locate the truing tool 46 for truing the periphery of the grinding wheel 13, the difference in radii of the concentric portions 115 and 116 being equal to the difference in the radius of the two respective grinding wheel faces to be trued.

The cam 100 is preferably rotated rapidly to position the truing tool 46 for its pass across the periphery of either the grinding wheel 12 or the grinding wheel 13. A hydraulically operated cam turning mechanism is provided comprising a cylinder 120 having a slidably mounted piston 121. A piston rod 122 is connected at one end to the piston 121 and at its other end to a rack bar 123 which engages a small gear or pinion 124 which is fixedly connected to rotate with the cam 110. A guide 125 is provided to guide the rack bar 123 and maintain it in mesh with the gear 124.

A cam plate 126 is mounted on the rear of the truing apparatus member 15 and is provided with a cam track 127 which is engaged by a square-shaped follower 128 which is either formed integral with or fixedly mounted on the lower end of the rack bar 123. The piston 121 and rack 123, therefore, cannot produce a rotary motion of the cam 110 while the truing tool 46 is traversing across the periphery of the grinding wheel. When fluid is admitted to start the traverse of the truing tool 46 toward the left to true the periphery of the grinding wheel 12, the cam 110

remains in the position illustrated in Fig. 2 with the concentric portion 115 engaging the follower 114. The parts remain in this position until the follower 128 travels along the cam track 127 into the position 128a so that it is free to travel in a vertical direction within the vertical portion 129 of the cam track 127. In this position of the parts at the start of the traversing operation, fluid under pressure from the pump 72 passing through the pipe 73 passes through a pipe 130, into a chamber 131 of a control valve 132, and passes out through a pipe 133, into a cylinder chamber 134, to exert a downward pressure on the piston 121 which serves through the rack bar 123 to cause the cam 110 to rotate in a clockwise direction to swing the concentric portion 116 of the cam 110 into engagement with the follower 114, thus rapidly lowering the truing tool 46 into position for truing the periphery of the grinding wheel 13. In this position, the follower 128 assumes the position 128b and engages the lower horizontal portion of the cam track 127 which prevents further rotation of the cam 110. The fluid pressure within the chamber 68 serves to traverse the truing tool 46 and slide 21 toward the left to pass the truing tool 46 across the periphery of the wheel 13 to true the same. This fluid pressure mechanism operates in the reverse manner as the truing tool and slide are traversed in the opposite direction on the return stroke.

During the downward movement of the piston 121, fluid within a cylinder chamber 140 exhausts through a pipe 141, a valve chamber 142, and out through a pipe 143 and a throttle valve 144 and a pipe 145 which connects with the exhaust pipe 82 to return the exhaust fluid to the reservoir 70. The throttle valve 144 is provided to regulate the exhaust of fluid from the cylinder 120 and thereby to regulate the rate of movement of the truing tool 46 and the rotary cam 110 in shifting from one diameter of wheel to the other.

The valve 132 is preferably arranged in axial alignment with the valve 69 and a common valve stem 146 connects the two valves so that they are actuated simultaneously by either the control knob 95 or the weighted arm 102. On the return stroke of the truing tool 46, the valve 132 is shifted into the reverse position so that fluid under pressure from the pump is admitted through the pipe 141 into the cylinder chamber 140 to produce an upward movement of the piston 121 when the truing tool has traversed to a predetermined position rapidly to raise the truing tool into position to true the larger diameter wheel 12.

The operation of this mechanism will be readily apparent from the foregoing disclosure. Assuming the throttle valves 81 and 144 have been previously adjusted, when it is desired to start a truing operation the knob 95 or the arm 102 is turned in a counterclockwise direction until the pawl 96 engages the notch 97 to latch the valve 69 in a starting position to start the traversing movement of the truing tool 46 toward the left. The truing tool traverses first at a rapid rate until it is about ready to contact with the periphery of the grinding wheel 12 whereupon the valve 83 cuts off the exhaust of fluid and fluid thereafter exhausts through the needle valve 81 to slow the traverse of the truing tool 46 down to a slow truing speed. This speed continues until the follower 128 reaches the position 128a (Fig. 2). The engagement of the follower 128

with the vertical portion 129 of the cam track 127 stops the longitudinal traversing movement of the truing tool and fluid under pressure passing through the pipe 133 into the cylinder chamber 134 causes a downward movement of the rack bar 123 to rotate the cam 110 in a clockwise direction which serves rapidly to lower the truing tool in a vertical direction into a position determined by the concentric portion 116 of the cam 110, which position locates the truing tool 46 in position accurately to true the periphery of the grinding wheel 13. When the follower 128 reaches the position 128b, the pressure still being on within the cylinder chamber 69, the slow traversing movement again starts to traverse the truing tool 46 across the periphery of the grinding wheel 13. After the truing tool finishes its traverse across the periphery of the grinding wheel 13, the speed is again increased during its idle movement toward the left until the dog or collar 99 engages the cam face 100 to withdraw the pawl 96 from the notch 97. Withdrawal of the pawl 96 releases the weighted arm 102 and the arm together with the valves 69 and 132 rotates in a clockwise direction to reverse the direction of flow of fluid within the system. The return traverse of the truing tool 46 is then completed in the reverse order, the tool traversing across the face of the grinding wheel 13, then 30 rising vertically due to actuation of the piston 121, and then traversing across the periphery of the grinding wheel 12, after which the truing tool continues its movement toward the right into an operative position and stops. The truing tool may be adjusted vertically before the truing operation is started or at any time during the truing operation, or at the left-hand end of its stroke, by rotation of the manually operable feed wheel 58.

40 It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

50 I claim:

1. In a wheel truing apparatus, a truing tool, a longitudinally traversable truing tool holder, means to traverse said holder and truing tool across the peripheries of a plurality of grinding wheels, means including a rotatable cam and a follower to move said tool toward and from the wheel periphery to position the truing tool for truing a plurality of closely spaced grinding wheels, means to stop the traversing movement of the truing tool, and means automatically to rotate said cam automatically to reposition the truing tool for truing an adjacent grinding wheel of different diameter.

65 2. In a grinding wheel truing apparatus, a truing tool, a longitudinally traversable truing tool holder, means to traverse said holder across the peripheral surfaces of a plurality of closely spaced multi-diameter grinding wheels, a rotatable cam and a follower to move said tool transversely toward and from the wheel periphery to position the truing tool for truing successive wheels, and an interlock which serves positively to stop the traverse of the truing tool and to hold it stationary until the rotation of the cam has repositioned the truing tool for truing an adjacent grinding wheel.

3. In a grinding wheel truing apparatus, a truing tool, a longitudinally traversable truing tool holder, means including a hydraulic piston and cylinder to traverse said holder and truing tool across the peripheral face of a grinding wheel, means including a cam and a follower to move said tool toward and from the periphery of the grinding wheel to true a predetermined shape thereon, means including a piston and cylinder operatively connected to actuate said cam rapidly to move the truing tool either toward or from the wheel periphery, and an interlock which serves positively to stop the traverse of the truing tool and hold it stationary during the automatic transverse positioning movement of the truing tool.

4. In a grinding wheel truing apparatus, a truing tool, a longitudinally traversable truing tool holder, means including a hydraulic piston and cylinder to traverse said holder and truing tool across the peripheral face of a grinding wheel, means including a cam and a follower to move said tool toward and from the periphery of the grinding wheel to true a predetermined shape thereon, means including a piston and cylinder operatively connected to actuate said cam rapidly to move the truing tool either toward or from the wheel periphery, and means including a track cam and a follower to govern and control the movement of said piston.

5. In a grinding wheel truing apparatus, a truing tool, a longitudinally traversable truing tool holder, means including a hydraulic piston and cylinder to traverse said holder and truing tool across the peripheral face of a grinding wheel, a rotatable cam and a follower to move the truing tool toward and from the periphery of the grinding wheel to true a predetermined shape thereon, means including a rack and pinion to rotate said cam, a fluid pressure piston and cylinder to actuate said rack and pinion, and means including a track cam and a follower connected to move with said piston to govern and control the movement of the piston.

6. In a grinding wheel truing apparatus, a longitudinally traversable truing tool holder, means to traverse said holder and truing tool across the peripheral faces of a plurality of grinding wheels of different diameters, means including a rotatable cam and a follower to move said tool transversely toward and from the peripheries of said grinding wheel, said cam having spaced concentric portions thereon to position the truing tool for truing the peripheral faces of different sized wheels, and means including a piston and cylinder operatively connected to rotate said cam so as quickly to shift the truing tool either toward or from the periphery of the wheel so as to position it for successively truing different diameters thereof.

7. In a grinding wheel truing apparatus, a truing tool, a longitudinally traversable truing tool holder, means to traverse said holder and truing tool across the peripheral faces of a plurality of grinding wheels of different diameters, means including a rotatable cam and a follower to move said tool transversely toward and from the peripheries of said wheels, means including a rack and gear mechanism to rotate said cam, and means including a fluid pressure cylinder and piston operatively connected to move said rack so as to produce a rapid transverse movement of the truing tool either toward or from the peripheries of said wheels, said cam having a plurality of

spaced concentric portions which serve to locate the truing tool for truing spaced grinding wheels.

8. In a grinding wheel truing apparatus, a truing tool, a truing tool holder, means to adjust the holder and tool relative to the vertical slide, a vertically movable slide therefor, a horizontal longitudinally movable slide which supports said vertical slide, means to reciprocate said horizontal slide so as to traverse the truing tool successively across the peripheral faces of a plurality of spaced grinding wheels of different diameters, means including a rotatable cam and a follower to move said slide vertically to position the truing tool in operative relation with successive grinding wheels, means including a rack and gear mechanism to rotate said cam, and means including a fluid pressure piston and cylinder operatively connected to actuate said rack and gear mechanism to rotate said cam.

9. In a grinding wheel truing apparatus, a truing tool, a truing tool holder, means to adjust the holder and tool relative to the vertical slide, a vertically movable slide therefor, a horizontal longitudinally movable slide which supports said vertical slide, means including a fluid pressure operated piston and cylinder to reciprocate said horizontal slide so as to traverse the truing tool successively across the peripheral faces of a plurality of spaced grinding wheels of different diameters, means including a rotatable cam and a follower to move said slide vertically so as to position the truing tool in operative relation with successive grinding wheels, means including a rack and gear mechanism to rotate said cam, means including a fluid pressure operated piston

and cylinder which are operatively connected to actuate said rack and gear mechanism, and means including a track cam and a follower which serves to govern and control the movement of said piston.

10. In a grinding wheel truing apparatus, a truing tool, a truing tool holder, means to adjust the holder and tool relative to the vertical slide, a vertically movable slide therefor, a horizontal longitudinally movable slide which supports said vertical slide, means to reciprocate said horizontal slide so as to traverse the truing tool successively across the peripheral faces of a plurality of spaced grinding wheels of different diameters, means including a rotatable cam and a follower to move said slide vertically to position the truing tool in operative relation with successive grinding wheels, means including a rack and gear mechanism to rotate said cam, said cam having a plurality of spaced concentric portions for locating the truing tool in position to true spaced wheels of different diameters, means including a piston and cylinder operatively connected to move said rack rapidly to rotate said cam and position the truing tool for truing a wheel of a different diameter, a follower which is fixedly connected with said rack and piston, and a track cam which serves to hold said piston stationary during the traverse of the truing tool across the periphery of said wheel, said track cam permitting rapid movement of said piston when the truing tool is shifted from one diameter to another.

CHARLES C. ALVORD. 35
